(57) **CLAIM**

The ornamental design for a charger for electric vehicle as shown and described.

DESCRIPTION

FIG. 1 is a front perspective view of a charger for electric vehicle showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a back perspective view thereof; and,

FIG. 9 is a front perspective view of the charger for electric vehicle shown in an environment of use.

The charging cables shown in broken lines in FIG. 9 show environmental structure only and form no part of the claimed design. All other broken lines shown in the drawings depict portions of the charger for electric vehicle that form no part of the claimed design.
